OF NEW YORK

ELECTRIC SIGNAL BELL

Application filed December 14, 1926. Serial No. 154,844.

The electric bell described herein and shown in the drawings belongs properly to the plunger-type vibrating bells, operable on an alternating current circuit, whereby no 5 sparking can occur, on account of the absence of open contact points, as now well known in alternating current practice. Its new features may well be employed in other types of electromagnetically operated devices. The 10 bell is particularly intended for places where the presence of inflammable gases would be dangerous when using electric make-and-break devices, or where the accumulation of dust makes it difficult or impossible to employ open contact points.

The main object of the invention is to simplify electric translating devices of this general type, for instance, electric bells, to make 20 their operation more effective and to lower their cost of construction.

One feature of the invention comprises the arrangement of resilient means to mechanically assist the electromagnetic vibrating means. Another one consists in providing 25 means for changing the distance of attraction of the armature in respect to the electromagnet, a further one includes means for changing the rate of vibration of the above mentioned resilient means, and additional 30 features will become apparent, as the description and operation of the invention justifies.

Electric bells of the plunger type are well known in the art, as for instance, in U. S. Patent No. 1,180,445. Means for mechanically 35 assisting the electromagnetic operation of a translating device are shown in U. S. Patents Nos. 1,052,354 and 1,066,929.

The improvements, however, claimed for this invention and thought to be broadly new 40 over the state of the art, relate particularly to the peculiar resilient, vibratory operation of the striker or plunger, as clearly described herein and shown in the drawings, in which Fig. 1 is a plan view of the invention, the 45 gong of the bell being removed and indicated

in dashed lines, Fig. 2, a side elevation and, in part, a vertical cross section in a plane parallel to the axis of the striker, and in Fig. 3, a perspective view of the armature of the electromagnet.

A frame or base 10 serves to support the entire organization of parts and carries an electromagnet 11, having, preferably, windings of enameled wire and a core 12 which may be of laminated construction. An armature 13, usually of the pivoted cylindrical-bearing type, is arranged adjacent to the open pole ends of electromagnet 11. The bearings, around which the armature vibrates, are indicated at 14.

Armature 13 carries a resilient member 15, in the form of a blade spring, secured to armature 13 at a point adjacent to the axis of its bearings and on that side of the armature which is opposite to the one contacting with the pole-ends of magnet 11. This member 15 is free to swing away from the magnet along its entire length, but restricted to swing toward magnet 11, by the body of armature 13. It may be reenforced by laminations 16 and 17, acting as auxiliaries.

A retractile spring 18, also carried by armature 13, has its free end resting on, or attached to and being adjustable by a stop 19. This adjustable stop is employed for 75 changing the distance between armature 13 and the pole-ends of magnet 11 and, therefore, for placing armature 13 more or less within the field of attraction of magnet 11, for regulating the operation of the bell or 80 other translating device.

A plunger or striker rod 20 is loosely secured at one end 21 to the free end of spring 15, while the other end passes through a guide post 22 and operates the gong 23, or 85 other translating device.

It should be noted that on the energization of magnet 11 and the attraction of armature 13, spring 18 is caused to press against stop 19, which, by being raised or lowered, 90

modifies the position of armature 13 within the field of attraction of magnet 11 and, thereby, the distance through which the armature is caused to travel. At the same time, spring 15 resiliently pushes striker 20 toward gong 23. On the other hand, on the deenergization of magnet 11, spring 18 retracts armature 13, and spring 15 pulls striker 20 away from gong 23.

10 Bell 23 in conjunction with striker 20 operates as a vibrating bell in which the bell is struck repeatedly as long as the circuit energizing the magnet 11 is closed. There are no contacts in the device, except the 15 single remote closing means for the circuit. When these means are closed and kept closed, the attraction and repulsion of armature 13 by magnet 11, is substantially in unison with the cycle of the alternating current used in 20 operating the bell. During each cycle, armature 13 will first be attracted by magnet 11 and then repelled. At each attraction, and after armature 13 is in momentary contact with magnet 11, striker 20, due to its inertia, 25 will continue to travel toward gong 23, and spring 15 will be bent at the upper end of armature 13 and to its connection with striker 20. At each repulsion, however, 30 spring 15 will be bent and partially separated from the armature substantially from the lower end of armature 13 and to its connection with the striker.

The resiliency of spring 15 while pulling, 35 is operating along its entire length and, much greater than when pushing, where it is limited by the rigidity of armature 13. The combined result is an operation of the reciprocating striker of such character of 40 stroke that when the circuit is momentarily closed the acoustic effect of the vibrating bell is similar to that of a single stroke bell and, for this reason, even capable of use and eminently satisfactory for code signaling according to the opening and closing of 45 the circuit at a remote circuit controlling device, such as a pushbutton or the code wheel of a signal transmitter.

We claim:—

- 50 1. In combination, an electromagnet, an armature, a striker, a translating device co-operating with said striker, means for resiliently biasing the armature away from the magnet, and means for resiliently connecting said striker with said armature and located on the face of said armature opposite to that adjacent to said magnet, the resiliency of said connecting means being greater when said armature is moving toward said magnet than when moving away from said magnet.
- 55 2. In combination, an electromagnet, an armature, a striker, means for resiliently holding said armature away from said magnet, a translating device cooperating with said striker, and means for resiliently connecting said striker with said armature and

located on the face of said armature opposite to that adjacent to said magnet, the resiliency of said connecting means being greater when said armature is moving toward said magnet than when moving away from said magnet.

In witness whereof, we have jointly signed the foregoing specification, at New York, in the county and State of New York, this 10th day of December, 1926.

70 FRANK ALBRIGHT.
